UNITED STATES PATENT OFFICE

JEAN W. BICKS, OF CHICAGO, ILLINOIS, ASSIGNOR TO C. A. ZOES MANUFACTURING CO., OF CHICAGO, ILLINOIS, A CORPORATION OF ILLINOIS

DESIGN FOR A BOTTLE OR SIMILAR ARTICLE

Application filed January 22, 1931. Serial No. 38,412. Term of patent 14 years.

To all whom it may concern:

Be it known that I, JEAN W. BICKS, a citizen of the United States, and a resident of the city of Chicago, in the county of Cook and State of Illinois, have invented a new, original, and ornamental Design for a Bottle or Similar Article, of which the following is a specification, reference being had to the accompanying drawings forming a part hereof.

On the drawings:

I claim:

The ornamental design for a bottle, or similar article, as shown.

JEAN W. BICKS.
